United States Patent Office

Des. 229,613

Patented Dec. 18, 1973

229,613

VEHICLE

Delles T. Davis, Abilene, and Bruce D. Motlong,
Midland, Tex., assignors to Research Fuels, Inc.

Continuation-in-part of abandoned design application Ser.
No. 24,450, Aug. 12, 1970. This application Nov. 11,
1971, Ser. No. 198,058

Term of patent 14 years

Int. Cl. D12—08

U.S. Cl. D14—3 G

Fig. 4

Fig. 5

Fig. 6

FIG. 1 is an elevation view of a vehicle showing our design as seen from the right side;

FIG. 2 is an elevation view showing our design as seen from the left side;

FIG. 3 is an elevation view showing our design as seen from the rear;

FIG. 4 is a plan view of the vehicle;

FIG. 5 is a bottom view of the vehicle;

FIG. 6 is an elevation view showing our design as seen from the front; and

FIG. 7 is an isometric view of the vehicle of the present invention.

This application is a continuation-in-part of our co-pending design application, D. 24,450, filed Aug. 12, 1970, now abandoned.

We claim:

The ornamental design for a vehicle, substantially as shown.
